[57] CLAIM

The ornamental design for a tea brewer, as shown and
described.

DESCRIPTION

FIG. 1 is a top, front, and left side perspective view of
a tea brewer showing my new design;

FIG. 2 is a right side elevational view thereof;

FIG. 3 is a top plan view thereof;

FIG. 4 is a rear elevational view thereof;

FIG. 5 is a bottom plan view thereof.

The stippled shading on the drawing represents contrast
only.
